US00D488482S

(12) United States Design Patent
Bungert

(10) Patent No.: US D488,482 S
(45) Date of Patent:  Apr. 13, 2004

(54) ICON FOR A PORTION OF A COMPUTER SCREEN

D461,478 S * 8/2002 Bungert
D471,205 S * 3/2003 Lane
D471,226 S * 3/2003 Gray
D476,016 S * 6/2003 Platz et al.

(75) Inventor: Ulrich Bungert, Stein (DE)

(73) Assignee: Siemens Aktiengesellschaft, Munich (DE)

() Term: 14 Years

(21) Appl. No.: 29/143,442

(22) Filed: Jun. 13, 2001

(30) Foreign Application Priority Data

Dec. 22, 2000 (DE) 4 00 12 148

(51) LOC (7) Cl. 14-02

(52) U.S. Cl. D14/489

(58) Field of Search D14/485-95; D18/24-33;
D19/6; D20/11; D21/324-33; 345/700-26,
764-866
